UNITED STATES PATENT OFFICE

ALGOT F. JOHNSON, OF MINNEAPOLIS, MINNESOTA, ASSIGNOR TO KOEHRING COMPANY,
OF MILWAUKEE, WISCONSIN, A CORPORATION OF WISCONSIN

SPRINKLING SYSTEM FOR USE WITH CONCRETE PAVING MACHINES

Application filed May 21, 1928. Serial No. 279,463.

This invention relates to a sub-grade sprinkling system for use with concrete road-paving apparatus, and has for its main object to provide an extremely simple and highly efficient sprinkling system for wetting down a road bed before the concrete is poured thereon.

In the accompanying drawing, which illustrates the invention, like characters indicate like parts throughout the several views.

Referring to the drawing:

Fig. 1 is a diagrammatic side elevation of several machines used in making concrete roads and diagrammatically illustrating my sprinkling system in connection with certain uses thereof;

Fig. 2 is a plan view of Fig. 1, some parts not shown;

Fig. 3 is a section taken on the line 3—3
20 of Fig. 1; and

Fig. 4 is a section taken on the line 4—4 of
Fig. 3.

The numeral 5 indicates a road bed, the numeral 6 concrete road side forms between which concrete is poured while making pavements, the numeral 7 a concrete road paving machine arranged to travel on the road bed under its own power, the numeral 8 a sub-grade planer arranged to travel on the side forms 6 behind the paver and to be drawn thereby through suitable connections including drawbars 9, and the numeral 9' a concrete road finishing machine arranged to travel on the side forms 6 over the road bed, after the concrete has been poured between the forms, for surfacing the concrete road.

The paving machine 7 comprises in part a main frame structure 10 that is mounted on a truck or the like 11, a charging skip 12, a mixing drum not shown, a discharge spout 13, a distributing boom 14, a distributing bucket 15 having a dump bottom 16, and operator's control mechanism. The control mechanism includes a steering wheel 17 and a lever 18, by manipulation of which wheels 19 of the truck or the like 11 will be caused to become operatively connected to a suitable source of power, not shown, for driving said paving machine over the road bed.

The sub-grade planer comprises a frame 20

mounted on wheels 21, arranged to run on the side forms 6, and road scraping members 22. Mounted on brackets 23 that are secured to and extend forward from the main frame 7 of the paving machine, is a long 55 sprinkler-distributing head 24 that is closed at both ends and is provided with a series of spraying nozzles 25. The distributing head 24 extends transversely over the road bed and the nozzles 25 are close enough together to insure an even distribution of water to the entire area of the road bed between the side forms over which the sprayer is moved. The distributing head 24 is connected to a source of supply, not shown, through a pipe line 27, 60 a hand-operated volume control valve 28, and an automatically actuated shut-off valve 29.

Mounted on brackets 30 carried by and extending to the rear of the frame 20 of the sub-grade planer 8, is a long sprinkler-distributing head 31 that is of the same description as the distributing head 24 and is provided with a series of spraying nozzles 32. The spray head 21 is connected to the supply tank 26 through a pipe 26', the hand-operated volume control valve 33, hose line 34, shut-off valve 29 and pipe line 27. The shut-off valve 29 is provided with an operating arm 35 that is operatively connected to the 75 control lever 18 by a link 36.

Road paving machines of the kind shown move over the road step by step. When the forms 7 have been filled with concrete for as great a distance as is possible from one 80 position, the machine is moved ahead to a desired position and stopped for further dumping of concrete between the forms. In order to make the machine go forward one step of movement, it is necessary to manipulate the control lever 18 and, hence, the shut-off valve 29 will be automatically opened and will remain open until the lever 18 is moved to an inoperative or normal position, at which time the shut-off valve 29 will be 85 closed and the sprinkler rendered inoperative. It is obvious that the sprinklers are always inoperative when the machine is stopped, but that they are always operative 90 when the machine is in motion, unless one 95

or both be shut off manually by the valves 28 or 33.

In order to keep the sprinkler from excessive dripping and forming puddles in the 5 road after the machine has been stopped and the shut-off valve closed, I extend the spraying nozzles 25 or 32 through and into the distributing heads 24 and 31. In this way, a 10 large percentage of the water is retained 15 within the system.

If road beds are not moistened before the concrete is poured, a large percentage of the water in the concrete is absorbed by the drying earth and highly efficient results can 15 not readily be obtained. It has been the common practice in the trade to sprinkle the road bed by the use of a hose or the like from the side of the road. This, of course, takes 20 considerable time and, also, this method is not always efficient, due to the fact that an even amount of moisture to all portions of the road is not likely to be obtained; some parts usually appear relatively dry, while 25 other parts will have puddles of water formed thereon.

By the use of my sprinkling system, any 30 desired amount of moisture may be applied evenly to all portions of the road bed, with little or no effort on the part of the crew. It 35 may, at times, be desired to use but one of the sprinkling devices and, in that case, the other may be thrown completely out of action by turning down the hand-operated volume 40 control valve 28 or 33.

35 What I claim is:

1. The combination with a paving machine 45 arranged to move over a road bed and pour concrete thereon, of a sub-grade leveling machine attached to said paving machine for movements therewith for action on the road before the concrete is poured thereon, of a 50 sprinkler carried by said leveling machine for distributing water on the road bed therebehind and ahead of the portion of the road being covered with concrete, and a sprinkler carried by the paving machine for distributing water on the road bed ahead of the leveling machine.

2. The combination with a paving machine 55 arranged to move over a road bed and pour concrete thereon, of a sub-grade leveling machine attached to said paving machine for movements therewith for action on the road before the concrete is poured thereon, of a 60 sprinkler carried by said leveling machine for distributing water on the road bed therebehind and ahead of the portion of the road being covered with concrete, a sprinkler carried by the paving machine for distributing water on the road bed ahead of the leveling machine, and means cooperative with certain 65 paving machine mechanism for cutting both of said sprinklers into and out of action automatically.

3. The combination with a paving machine

arranged to move over a road bed and to pour concrete thereon, and a subgrade levelling machine attached to the paving machine for movements therewith for action on the road before the concrete is poured thereon, of 70 sprinkling means carried by the levelling machine for distributing water on the road bed therebehind and ahead of the portion of the road being covered with concrete, a second 75 sprinkling means carried by the paving machine for distributing water on the road bed in advance of the paving machine, a supply line for heading water from a source of 80 supply to the sprinkling means, means under control of an operator for selectively bringing 85 the respective sprinkling means into and out of operation, and means for automatically rendering operative and inoperative the supply of water passing through the supply line as the paving machine placed into and out of 90 movement along the road bed.

In testimony whereof I affix my signature.

ALGOT F. JOHNSON.
